INVENTOR
FRANK PARDEE.

BY
Anthony Meira ATTORNEY

UNITED STATES PATENT OFFICE.

FRANK PARDEE, OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA.

SPIRAL RUNWAY.

Application filed August 31, 1927. Serial No. 216,525.

This invention relates to improvements in spiral runways and to the method of manufacturing the same such as described in my co-pending application Serial No. 203,764 filed July 6, 1927. In one embodiment of the invention illustrated, the spiral runway is self-supporting. That is to say, it is strengthened vertically so that it does not require any supporting uprights. The usual form of runway such as heretofore used for conveying materials from a higher to a lower level or runways used in the separation of different materials have been made in separate segments joined to one another in various ways. Where it has been desirable to provide an upright wall along the outer edge of such a runway, the same has usually been formed of a separate piece, bolted, bracketed or otherwise secured to the floor or bottom wall of the runway. Built-up runways are costly to fabricate and assemble.

My improved runway avoids the above objections and provides an improved runway which is light in weight yet amply strong to withstand the severe service to which this class of apparatus is subjected. The embodiment of the runway illustrated is formed of sheet metal having integral side and bottom walls, the blank from which the runway is formed being obliquely slit or cut at spaced intervals and the portions or segments thus formed being inwardly bent and overlapped in the manner more fully described herein-after.

Embodiments of the invention are illustrated in the accompanying drawings in which—

Fig. 1 is a front view of a self-supporting spiral runway embodying my invention;

Fig. 2 is a plan view of a runway built in accordance with the invention;

Fig. 3 is a sectional view on line 3—3 of Fig. 2;

Fig. 4 is a view of a blank from which sections of the runway are constructed;

Figs. 5, 6 and 7 show successive steps in bending the blank of Fig. 4 to form the runway shown in Figs. 1 and 2;

Figs. 8, 9, 10 and 11 are diagrammatic illustrations illustrating steps in the method of forming my improved runway;

Fig. 12 is a detail view of a modified embodiment of the invention, the view being a horizontal section;

Fig. 13 is a vertical section on line 13—13 of Fig. 12;

Figs. 14 and 15 are horizontal sections of further modifications;

Fig. 16 is a horizontal section of a modification in which the runway is formed of bent plates secured by clips to upright members;

Fig. 17 is a detail view of a blank from which the sections shown in Fig. 16 are formed;

Fig. 18 is a view similar to Fig. 16 but showing a self-supporting runway.

Referring in detail to the drawings, the runway illustrated is formed of a plurality of substantially spiral sections 14, each section constituting approximately a one-quarter turn of the spiral. It is to be understood, however, that if desired, the sections may be as illustrated in Fig. 3, the sections being connected with one another by suitable splice plates 15. Or, the sections may be made each in one full turn as shown in Fig. 1. Each section of the runway comprises a side wall 20 and an integral floor or bottom wall 22 which is inclined inwardly and downwardly toward the central axis of the spiral runway. The floor or bottom wall is joined to the side wall 20 by an inclined fillet portion 24. The floor or bottom wall 22 may be said to be formed of a plurality of segments 26. The segments 26 overlap one another as shown in Figs. 1 and 2 and near their inner edges they are secured to one another by suitable fastening means such as the bolts 28. It is understood that these overlapping parts may be otherwise secured, for example, by welding, riveting, etc.

In manufacturing my improved runway, I employ a novel method which includes providing a blank B of sheet metal of suitable thickness, the sides b and b¹ of which are substantially parallel. In its initial state the blank is of approximately rectangular form and the triangular pieces indicated by the broken lines c and d are cut off each end. This leaves the ends e and f oblique. I next scribe two lines h and i parallel with the sides b, b¹. I next cut away portions of the blank so as to leave the acute triangular openings k extending obliquely as shown in Fig. 3, the center lines of these openings being approximately parallel with the edges e and f. I next double over the

blank along the dotted line indicated at *b* so that the blank has a double thickness along one marginal edge. This completes the flat blank. The next step is to 5 roll the flat blank *B* into substantially spiral form. This is accomplished by feeding the blank *B* in the direction of the arrows *z* in Fig. 8 toward the rolls *l*. These rolls curl the blank *B* into substantially spiral form. 10 In plan, the blank is thus curved on an arc of a circle and in the case illustrated, the length of blank is sufficient to make a quarter section as illustrated in Figs. 5 and 9. The curled blank of Fig. 5 is then subjected to the action of suitable bending rolls 15 *m* and *n* (Fig. 10) so as to transversely bend portion of the blank along the line *h*. This step will slightly overlap the segments 26 and the blank will have the appearance shown 20 in Fig. 6. The next operation comprises subjecting the partly formed blank of Fig. 6 to the action of suitable bending rolls *o* and *p* so as to again bend the blank along the line *i*. This will decrease the included angle 25 between the side wall 20 and the bottom wall 22 as will be readily understood. This last step will produce a predetermined degree of inclination which degree of inclination can, of course, be varied to suit the particular 30 requirement for which the runway is to be used.

Fig. 7 illustrates the final bending effected by the rolls *o*, *p*. This provides a substantial overlap along the contiguous portions of 35 the adjacent segments 26. These segments are then suitably secured to one another, for example, by means of bolts 28 or they may be spot welded or various forms of interlocking joints may be secured by depressing part of 40 one segment into a depression in the underlying segment.

While I have illustrated the runway as built-up of quarter sections, it is understood that this is merely illustrative and I 45 contemplate rolling the blanks also in half turns or full turns or, if desired, in multiple turns and fractions of turns.

By bending over the outer upper marginal portion, the runway is materially strengthened 50 against flexure in a longitudinal or axial direction, it being apparent that this provides an outer spiral reinforcement 18 which so rigidifies the runway structure that it becomes self-supporting.

However, it is understood, of course, that if desired, for certain classes of work, I may provide outer uprights such as angle irons or the like located at spaced points around the periphery or I may utilize a central axial 55 post having rigidly extending arms on which the runway rests and to which it may be secured.

While I have referred to the use of bending rolls for the purpose of forming up the blank 60 to the required shape of runway, it is also

within my invention to cut the blank in one operation of the press and to form it to the desired shape in another operation by the use of a suitable press and dies.

In the embodiment of the invention shown 70 in Figs. 12 and 13, the runway is composed of cast iron sections 30 of substantially the shape shown in Fig. 13, each section being thickened at the point 32 which is located in the zone where the greatest wear occurs. 75 Each section 30 is formed with an outwardly extending hook-like portion 34 which is adapted to engage the flanges 36 of an upright T-bar 38. Certain of the sections 30 will be provided with integral dowel-like 80 extensions 40 which will engage recesses formed in the section next adjacent it so as to secure the parts in proper alignment. The sections will be bolted to one another and also to the upright by means of a suitable 85 bolt such as indicated at 42. It is apparent that when the bolt 42 is drawn up tight, that it will clamp the hook-like extensions 34 against the flanges of the upright 38 and will also draw the adjacent sections toward one 90 another. Fig. 14 shows a similar arrangement in which the extensions 34 are formed with curved seats so as to fit snugly against the pipe-like or tubular upright member 44. Fig. 15 shows a slight modification of 95 the preceding figures, the extensions 34 being shaped to interfit with an upright 46 formed of an ordinary angle bar. In the arrangement of Fig. 16, the runway is built of 100 sheet metal plates similar in many respects to that illustrated in Figs. 1 to 10 inclusive. Each section, however, is formed with outwardly extending flanges 48 for coaction with clips 50 which are shaped for engagement with suitable upright as indicated at 105 52. The clips 50 and also the flanges 48 are provided with a suitable perforation through which the securing bolt 54 passes. Fig. 17 shows the blank from which the sections of 110 Fig. 16 are made. The flanges 48 are formed by bending the blank on the dotted line 56. Otherwise, this blank is formed in substantially the same manner as the blanks illustrated in Fig. 4.

In Fig. 18 I have illustrated in plan a portion of the runway, the sections of which are provided with flanges 48 which are bolted directly to one another by means of bolts 58. Each section of this construction will preferably, though not necessarily, be made 115 in segments of one-eighth of a turn. Such a runway will have sufficient stiffness to stand up itself without the use of uprights such as angle bars or tubing.

The flanges shown need not be exactly vertical, the term upright being used herein to refer to flanges occupying a sufficient component vertically to secure the desire results. The important thing is that the depth of the runway in cross-section, that is, the vertical 120 125 130

distance from the lowest to the highest point of it, be sufficient to secure the desired stiffness against vertical strains; to make the structure entirely self-supporting in the style 5 shown in Fig. 1 or stiff enough to carry the weight of the runway and its load between uprights in designs such as that of Fig. 12.

The cross-section indicated at the right and left of Fig. 3 shows that the floor is inclined downward toward the center. This, combined with the downward spiral pitch, makes the coal or other material flow at the points of discharge toward the center and at an angle of least impact against the material ahead of it. Thus, breakage of the material is kept down to a minimum. The design shown permits the free discharge of materials on the inside edge of the runway and causes them to pile up around the spiral 20 gradually from the central bottom point upward.

Various modifications may be made by those skilled in the art without departing from the invention as defined in the appended 25 claims.

What I claim is:—

1. A spiral runway having a floor and an outer integral upright flange having a portion overlapped to strengthen the structure.
2. A spiral runway having a floor and an outer integral upright overlapped flange of greater thickness than the floor.
3. A spiral runway having a floor and an upright flange integral therewith, said floor comprising a plurality of inwardly bent segments integral with said flange.
4. A spiral runway having a side and a bottom wall formed of a single integral sheet, said bottom wall comprising a plurality of inwardly bent overlapping segments and said side wall having an overlapped portion adapted to strengthen the structure against vertical deflection.
5. A spiral runway having a plurality of overlapping bottom segments which are integral parts of a single member.
6. A spiral runway having a side and a bottom wall formed of an integral sheet, said bottom wall having a plurality of overlapping bottom segments.
7. A spiral runway having a side and a bottom wall formed of an integral sheet, said bottom wall having a plurality of obliquely cut portions bent into overlapping relationship.
8. A spiral runway having a side and a bottom wall formed of an integral sheet, said bottom wall having a plurality of overlapping bottom segments, and means for securing them in such relationship.
9. A spiral runway comprising a series of sections arranged end to end, each section

comprising an integral sheet metal side and a bottom wall and each bottom wall having a plurality of cut portions bent inward from 65 said side wall to form a series of flat inclined segments which approximately conform to a spiral.

10. A spiral runway section adapted to be combined with other similar sections to form 70 a continuous spiral structure comprising a substantially vertical side wall and a bottom wall integral with the side wall composed of a series of inwardly bent flat segments.

11. A spiral runway section adapted to be combined with other similar sections to form 75 a continuous spiral structure comprising a substantially vertical side wall and a bottom wall composed of a series of inwardly bent flat segments having portions which overlap 80 said segments being integral with said side wall and means securing the overlapped portions to one another.

12. In the manufacture of spiral runways, the method which consists in providing a 85 flat sheet metal blank having substantially or approximately parallel sides, making a series of oblique slots which extend from one side of said blank toward the other, curling the sheet to substantially spiral form, then 90 bending the cut portion of the curled sheet transversely inward to cause an overlapping of the segments between the cut portions.

13. In the manufacture of spiral runways, the method which consists in providing a 95 flat sheet metal blank having substantially or approximately parallel sides, making a series of oblique slots which extend from one side of said blank toward the other, curling the sheet to substantially spiral form, then 100 bending the cut portion of the curled sheet transversely inward to cause an overlapping of the segments between the cut portions, then bending the cut portion again to increase the amount of overlap.

14. In the manufacture of spiral runways, the method which consists in providing a flat sheet metal blank having substantially or approximately parallel sides, making a series of oblique acute angular slots which extend from one side of said blank toward the other, curling the sheet, then bending the cut portion throughout its length substantially on the line at which the cuts terminate and then again bending the cut portion along 110 a line substantially parallel with the first line so as to decrease the included angle between the cut and uncut portions and thus produce a predetermined downward and inward inclination of the bottom wall of the runway.

In witness whereof, I have hereunto signed my name.

FRANK PARDEE.
